(57) CLAIM

The ornamental design for a snowboard hook, as shown and described.

DESCRIPTION

FIG. 1 is a perspective view showing environmental structures of a snowboard hook attached between a boot and a snowboard with open binding, with the snowboard, binding, and boot shown in phantom.

FIG. 2 is a magnified detail view of FIG. 1, showing the snowboard hook attached to the boot and binding, with the boot and binding shown in phantom.

FIG. 3 is an isometric view of a snowboard hook, taken from a top front left perspective.

FIG. 4 is an isometric view of a snowboard hook, taken from a top rear right perspective.

FIG. 5 is an isometric view of a snowboard hook, taken from a top front right perspective; and,

FIG. 6 is an isometric view of a snowboard hook, taken from a bottom front left perspective.

The broken lines in the drawing depicting the boot, binding, and snowboard are for illustrative purposes only and form no part of the claimed design.
